HENRY HUDSON URQUHART, OF ST. LOUIS, MISSOURI, ASSIGNOR OF ONE-TENTH TO
JOHN W. MYERSCOUGH, OF ST. LOUIS, MISSOURI.

PILE-LIFTING JACK.

1,410,968.

Specification of Letters Patent. Patented Mar. 28, 1922.

Application filed February 16, 1921. Serial No. 445,478.

To all whom it may concern:

Be it known that I, HENRY H. URQUHART, a citizen of the United States, residing at St. Louis city and State of Missouri, have 5 invented a new and useful Pile-Lifting Jack, of which the following is a specification.

This invention relates to jacks adapted to pull piles or sheet piling and concrete forms out of the ground.

10 Objects of the invention are to provide a jack which is quickly adjustable, which is operated with a minimum of labor, which will save the material, and which will pull forms ordinarily left in the ground because 15 of a lack of such device.

The invention also provides means whereby concrete forms of all descriptions may be wrecked.

20 The invention will be best understood from a consideration of the following detailed description taken in connection with the accompanying drawing forming part of this specification, with the understanding, however, that the invention is not confined 25 to any strict conformity with the showing in the drawing, but may be changed and modified so long as such changes and modifications mark no material departure from the salient features of the invention as expressed 30 in the appended claims.

In the drawing:

Fig. 1 is a perspective view of the improved pulling and lifting tool.

Fig. 2 is a vertical sectional view of the 35 same on an enlarged scale, parts being broken away.

Fig. 3 is a horizontal sectional view.

Fig. 4 is a perspective view of one form of chain receiver.

40 Fig. 5 is a similar view of a slightly modified form of the chain receiver.

The invention includes a base 10, to which a pair of standards 11 are secured, the standards preferably being cast along with 45 its base. These standards are parallel and each has a channel 12 on its inner face, and a slot 13 extending longitudinally of each standard the greater part of the length thereof. Slidably received within each channel 12 is a bar 14 having ratchet teeth 15 on one longitudinal edge. Each bar 14 has a plurality of tapped bores 17 for receiving a stud 16, which stud projects through the cor-

responding slot 13 whereby the two bars are held in their channels.

55 Each of the standards along one edge is provided with a pair of spaced ears 18 and a passageway is provided between said ears for the swinging of the rack-engaging end 20 of the pawl 19. A spring 21 bears against 60 the part 20 so as to normally hold said part in the channel 12 and hence in engagement with the teeth 15. At the upper end and intermediate of each bar 14 pairs of perforations 22 are provided, the perforations of 65 each pair being in alinement with each other horizontally. Pivottally mounted between the bars 14, by trunnions insertible into either pair of perforations is a rock arm 23 having a socket in one end to receive a handle 70 24. The other end of the rock arm is provided with a square socket 25 into which the neck of a chain receiver fits. The two forms of chain receivers, as shown in Figs. 4 and 5, are alike in that each includes a square shank 75 or neck that is perforated to receive a bolt 27 passing also through the rock arm. The chain receiver 26 is shown as having three perforations 29 whereby the extent of its projection beyond the end of the rock arm may 80 be varied. The head of the chain receiver 26 is provided with a plurality of claws 28, these claws being designed to engage with the links of a chain. The chain receiver 26 has two pairs of these claws on opposite 85 sides. The chain receiver 30 has a single pair 31 projecting longitudinally.

The rock arm 23 has gudgeons or trunnions projecting from opposite sides and including the enlarged portions 32 which are 90 substantially frusto-conical in shape and the reduced cylindrical portions 33 which are received within bearings in the bars 14. The rock arm swings between the standards independently of the position of the bars with 95 respect to said standards.

There are many uses to which the invention may be put. The chain or cable may be secured at one end to the object to be lifted or pulled and wrapped about the claws 100 of either of the heads 26 or 30, as the case may be. Then the height of the rock arm above the ground or other support is adjusted by raising or lowering the bars 14. The pull upwardly on either bar will carry with 105 it the rock arm and the other bar, the end

20 of the detent or pawl moving outwardly as each tooth 15 comes in contact therewith. When the desired adjustment has been obtained, the pawls or detents will hold the 5 ratchet bars from downward motion. Then the object may be moved by pushing downwardly on the handle 24. It will be clear that if the object is embedded in the ground, the rack bars should first be adjusted in their 10 low position and after the object has been moved as far as may be possible, the bars and rock arm will be moved upwardly, whereupon the pulling will be repeated. Thus little by little the most stubbornly 15 retained concrete form will be pulled out of the ground, whereupon the form may be used over again. The device saves time, labor and material and is useful not merely in pulling the objects out of the ground but 20 wherever heavy beams, girders or the like must be lifted a short distance.

The rock arm 23 is rotatable between the standards so that if the handle is removed the arm may be reversed to work on either 25 side of the tool without shifting its position.

What is claimed is:

1. In a device of the character described, a support, a pair of rack bars vertically adjustable on the support, a rock arm swing- 30 able between the rack bars and vertically adjustable thereon, a handle on one end of the rock arm, and a chain receiver adjust- ably carried upon the other end and ad- justable to extend the effective length of 35 said arm.

2. In a device of the character described, a support, a pair of rack bars vertically adjustable on the support, a rock arm swing- 40 able between the rack bars and vertically adjustable thereon, and cooperating means provided on the support and also on the rack bars whereby the height to which the bars may extend above said support can be controlled, said means also serving to hold 45 the bars to the support.

3. In a device of the character described, a support, a pair of rack bars vertically adjustable on the support, a rock arm swing- 50 able between the rack bars and vertically adjustable thereon, cooperating means pro- vided on the support and also on the rack bars whereby the height to which the bars may extend above said support can be controlled, said means also serving to hold the 55 bars to the support, a handle on one end of the rock arm, and a chain receiver adjust- ably carried upon the other end and ad- justable to extend the effective length of said arm.

60 4. In a device of the character described, a base, a pair of parallel vertical standards rising from the base, each standard being channelled and slotted longitudinally, a rack 65 bar slid able in each channel, means on each bar and cooperating with the slot to main-

tain the bar in its channel and act as a stop for the bar, and means on each standard and engaging with the teeth of the rack for maintaining the bars in adjusted vertical positions.

5. In a device of the character described, a base, a pair of parallel vertical standards rising from the base, each standard being channelled and slotted longitudinally, a rack bar slid able in each channel, means on each 70 bar and cooperating with the slot to maintain the bar in its channel and act as a stop for the bar, means on each standard and engaging with the teeth of the rack for maintaining the bars in adjusted vertical 75 positions, and a rock arm revolvably mounted between the rack bars.

6. In a device of the character described, a base, a pair of parallel vertical standards rising from the base, each standard being 80 channelled and slotted longitudinally, a rack bar slid able in each channel, means on each bar and cooperating with the slot to maintain the bar in its channel and act as a stop for the bar, means on each standard and 85 engaging with the teeth of the rack for maintaining the bars in adjusted vertical 90 positions, and a rock arm revolvably mounted between the rack bars, said rock arm carry- 95 ing a removable handle at one end and a removable and longitudinally adjustable chain receiver at the other end.

7. In a device of the character described, a base, a pair of parallel vertical standards rising from the base, each standard being 100 channelled and slotted longitudinally, a rack bar slid able in each channel, means on each bar and cooperating with the slot to maintain the bar in its channel and act as a stop for the bar, means on each standard and 105 engaging with the teeth of the rack for maintaining the bars in adjusted vertical 110 positions, a rock arm revolvably mounted between the rack bars, and means for adjusting the position of the rock arm longitudi- 115 nally of the rack bars.

8. In a device of the character described, a base, a pair of parallel vertical standards rising from the base, each standard being channelled and slotted longitudinally, a rack 115 bar slid able in each channel, means on each bar and cooperating with the slot to maintain the bar in its channel and act as a stop for the bar, said means being adjustable longitudinally of the bar whereby the extent to which the bars may be raised can be varied, and means on each standard and en- 120 gaging with the teeth of the rack for main- taining the bars in adjusted vertical posi- 125 tions.

9. In a device of the character described, a base, a pair of parallel vertical standards rising from the base, each standard being channelled and slotted longitudinally, a rack 130 bar slid able along said standard, and means

on each bar and cooperating with the slot to maintain the bar in its channel and act as a stop for the bar, means on each standard and engaging with the teeth of the 5 rack for maintaining the bars in adjusted vertical position, and a rock arm revolvably mounted between the rack bars and capable of being positioned at different points intermediate the length of said bars, said rock

arm having a removable handle at one end 10 and a removable chain receiver, said chain receiver being mounted so as to extend the effective length of the rock arm.

In testimony that I claim the foregoing as my own, I have hereto affixed my signature. 15

HENRY HUDSON URQUHART.
